UNITED STATES PATENT OFFICE.

ALLEN JOHNSTON, OF OTTUMWA, IOWA.

BUTTON-ATTACHING MACHINE.

1,110,794.

Specification of Letters Patent. Patented Sept. 15, 1914.

Application filed September 26, 1913. Serial No. 791,955.

To all whom it may concern:

Be it known that I, ALLEN JOHNSTON, a citizen of the United States, residing in Ottumwa, in the county of Wapello and State of Iowa, have invented a new and useful Improvement in Button - Attaching Machines, of which the following is a specification.

This invention relates to improvements in button attaching machines and more particularly to machines for attaching shoe buttons to shoes.

Objects of the invention are to provide a machine of the type above indicated which is of simple construction, of high capacity and which automatically accommodates itself to the attaching of buttons of different sizes.

Another object of the invention is to provide a button attaching machine in which the wire, which forms the attaching staple, is fed through the eye of the button severed and formed into a staple at one station and the button with its staple moved to another station where the staple is clenched to the shoe or other article, thereby providing ample time for the operator to place the shoe or other article to which the buttons are to be attached in proper position and without danger of displacing the buttons during the wire feeding and staple forming operation.

The invention furthermore consists in the improvements in the parts and devices and in the novel combinations of the parts and devices as herein shown, described and claimed.

In the drawing forming a part of this specification, Figure 1 is a top plan view of a machine embodying my improvements, parts being broken away and other parts being shown in section to better illustrate the mechanism. Fig. 2 is a side elevation of the machine shown in Fig. 1, several of the parts being shown in section to better illustrate their construction and operation. Fig. 3 is a horizontal sectional view taken substantially on the line 3—3 of Fig. 2, the gear on the driving shaft being shown in full. Fig. 4 is a vertical sectional view taken substantially on the line 4—4 of Fig. 2; and Figs. 5, 6 and 7 are detail sectional views showing three different positions of the disk and adjacent parts employed in cutting, forming the staple and clenching it to the fabric, Fig. 5 showing the position where

the wire which forms the staple has just been fed through the eye of the button, Fig. 6 showing the position of the parts when the wire has been severed and the staple formed and Fig. 7 showing the position of the parts just prior to the staple being clenched to the fabric.

In said drawing the machine is shown as having a base 10 on which may be mounted a motor 11 for driving the parts, the motor 11 having secured to the armature shaft thereof a small gear 12 meshing with a larger gear 13 secured to a horizontally extending driving shaft 14 mounted in suitable bearings on the base 10. Mounted in bearing 15 and parallel to the shaft 14 is a short oscillatable shaft 16, to the outer end of which is secured an annular disk 17 having slidably mounted therein a bar 18 which acts as a staple driver, as will appear hereinafter, the upper end of which is provided with a slot or recess 19 adapted to receive the eyes 20 of the shoe buttons 21 which feed by gravity down a chute 22 secured to a bracket 23 attached to the machine. Bodily movable with the bar 18 and also independently movable thereon is another bar 24 having a recess 25 at the outer end thereof adapted to receive the heads of the buttons 21 and, as more clearly shown in Fig. 2, the bar 24 is yieldingly pressed outwardly by a coil spring 26 and is limited in its movements relatively to the bar 18 by pin 27 and slot 28. The inner end of the shaft 16 has secured thereto a lever arm 29 to which is pivotally connected a link 30, the other end of which is pivotally connected to a rocking lever 31 operated by a cam 32 secured to the shaft 14, said lever 31 being held in engagement with the cam 32 by a spring 33.

The periphery of the disk 17 moves between two stationary members 34 and 35 (see Figs. 5 and 6), the member 35 having a wire guide 36 therethrough and the member 34 forming a guard or stop to limit the amount of wire 37 which is fed during each cycle to form the staple. The wire 37 is preferably fed from a reel by a lever 38 having a spring-held finger 39 thereon, the lever 38 being secured to the upper end of a short, vertical shaft 40, to the lower end of which is fixed a spring-controlled lever 41 operated by cam 42 on the shaft 14. A spring-controlled detent 43 is provided to prevent accidental retraction of the wire when the lever 38 is oscillated. The member 35, at

including, in combination: an oscillatable member movable from one position to another and having a period of rest at each position, means for feeding a button to said member, a staple driver mounted on and carried by said member, a staple former co-operable with said member after the button has been fed and when the latter is in one position to form a piece of wire passed through the eye of the button into a staple, a clenching die co-operable with said driver when said member is in its other position, and mechanism for oscillating said member, substantially as specified.

By referring to Fig. 2, it will be seen that the cam 47 is provided with a cut-out portion or fall 48 and rise 49. As shown in said figure, the bell-crank 45 is about to be depressed to sever the wire 37, at which time the plunger 50, carried thereby, will carry the lowermost shoe button down with it, after the wire has been fed through the eye of the button as will be understood. As soon as the wire has been severed, it will be carried down by the plunger 50, which in co-operation with the disk 17, acts as a staple former, along with the button as shown most clearly in Fig. 6 and the wire will thereby be formed into a staple. During this downward movement of the plunger 50 the bar or staple driver 18 is moved also until the same comes into engagement with an adjustable shoulder 51.

As shown in the drawing, the lower end of the plunger 50 is provided with a groove 52 to receive one edge of the button eye and the disk 17 is provided with radially arranged grooves 53 to receive the wire forming the staple. Alined with the grooves 53 on the periphery of the disk 17 are also notches 54 which receive the wire 37 before it is cut off to thereby properly position the same. After the wire has thus been severed and the staple formed, the bell-crank 45 will be oscillated to thereby raise the plunger 50 and knife 44 to such an extent as to clear the disk 17 but not far enough to permit the remaining buttons in the chute 22 to move downwardly. At this time, the disk 17 will be given a quarter turn by means of the lever 31 and intermediate mechanism connecting the shaft 16. This will bring the button with the staple opposite a clenching die 55 mounted on the upper end of one arm of another bell-crank lever 56, the other arm of which carries an antifriction roller 44 in engagement with and operated by a cam 57 secured to the shaft 14. When the disk 17 has been given the quarter turn, as above described, the bell-crank 56 will be oscillated, it being understood that the fabric 58 has been previously positioned between the clenching die 55 and the disk 17, and substantially simultaneously therewith a rock-arm 59 will be moved toward the disk 17 by a cam 60. The rock-arm 59 engages the extended end of the bar 18 and pushes the same with the button and staple outwardly, thereby causing the staple to perforate the fabric 58 and be clenched thereon by the die 55. After the staple has thus been clenched, the bell-crank 56 will be oscillated

back to its normal position thereby permitting the operator to extract the button from the recess in the disk 17 after which the disk 17 will be turned back through a quarter revolution and the operations repeated. After the disk 17 has been returned back to the position shown in Fig. 2 the roller 46 on the bell-crank 45 will drop into the recess 48 which raises the plunger 50 with a short, quick motion and allows the lowermost button in the chute 22 to fall into place on the members 18 and 24 after which the wire will be fed through the eye of the button and the cycle of operations repeated. To keep the bell-crank 56 in engagement with its operating cam, a spring 61 is provided and a coil spring 62 is secured at its ends to the bell-crank 45 and rock-arm 59 to keep these parts in engagement with their corresponding operating cams.

From the foregoing description, it will be seen that ample time is provided for the operator to insert the shoe or other article to which the buttons are to be attached between the die 55 and the disk 17, and furthermore that the button and staple will be kept in position in the disk 17 after the staple has been formed by the frictional engagement between the staple and the walls of the grooves 53, thereby preventing danger of any of the parts becoming displaced or disarranged. The yieldingly mounted bar 24 adapts the machine automatically for operation on buttons of different sizes without the necessity of adjusting any of the parts and also serves to provide a yieldable clamp for the button while the wire for the staple is being fed through the eye thereof.

Although I have herein shown and described what I now consider the preferred embodiment of my improvements, yet it will be understood that various changes and modifications may be made in the details of construction and arrangement of parts without departing from the spirit of the invention, and all such changes and modifications are contemplated as come within the scope of the claims appended hereto.

I claim:

1. A machine of the character described including, in combination: an oscillatable member movable from one position to another and having a period of rest at each position, means for feeding a button to said member, a staple driver mounted on and carried by said member, a staple former co-operable with said member after the button has been fed and when the latter is in one position to form a piece of wire passed through the eye of the button into a staple, a clenching die co-operable with said driver when said member is in its other position, and mechanism for oscillating said member, substantially as specified.

2. A machine of the character described

disk; a staple driver slidably mounted on said disk; a staple former coöperable with said disk when the latter is in one position to thereby form a staple from a piece of 5 wire; a clenching die coöperable with said driver when the disk is in another position, said disk having a recess therein in which a button having a staple through its eye is adapted to be carried from the first named 10 position to the second named position, substantially as specified.

3. A machine of the character described including, in combination: automatically operated wire feeding and cutting means, a 15 member having a recess therein adapted to be positioned adjacent the wire cutting means, means for feeding a button into said recess, and a staple former coöperable with said member and movable into said recess to 20 form a staple from a cut piece of wire, the staple passing through the eye of a button and said recess having grooves therein adapted to receive the formed staple, substantially as specified.

25 4. A machine of the character described including, in combination: a chute arranged to contain buttons to be fed by gravity, a member located adjacent the lower end of said chute and having a yieldably mounted 30 rigid bar therein, said bar having a recessed end adapted to receive a button head, wire feeding and cutting mechanism, and a former coöperable with said member to bend a cut piece of wire passing through the eye 35 of a button into a staple, the former also coöperating with said yieldably mounted bar to yieldingly clamp a button during the staple forming operation, substantially as specified.

40 5. A machine of the character described including, in combination: a recessed member: a staple driver slidably mounted on said member, said driver having its ends slotted and adapted to receive the eye of a 45 button; a yieldingly mounted bar having an end recessed and adapted to receive the head of a button; and a former coöperable with said recessed member to form a staple from a piece of wire passing through the eye of a 50 button, said former also cooperating with said bar to yieldingly clamp a button therebetween during the staple forming operation, substantially as specified.

55 6. A machine of the character described including, in combination: a chute arranged to contain buttons to be fed by gravity; a recessed member located adjacent the lower end of said chute and having a staple driver 60 slidably mounted thereon, said driver being slotted at one end and adapted to receive the eye of a button; a yieldingly mounted bar on said member having a recessed end adapted to receive the head of button; and a former movably mounted relatively to said 65 member and coöperable therewith to form a

staple from a piece of wire, said former also coöperating with said bar to yieldingly clamp the button during the staple forming operation, said former being movable across the end of said chute and assisting in 70 timing the feeding of the buttons, substantially as specified.

7. A machine of the character described including, in combination: a chute arranged to contain buttons to be fed by gravity; a 75 movably mounted member disposed adjacent the lower end of said chute, said member having a recess therein in which is slidably mounted a staple driver, said driver being recessed at one end to receive the eye 80 of a button; a former movable back and forth past the end of said chute and coöperable with said member to form a piece of wire into a staple, said former when in front of the end of said chute preventing 85 feeding of the buttons; a clenching die; and mechanism for moving said member to bring the staple formed adjacent the feed chute to a position adjacent said clenching die, substantially as specified.

90 8. A machine of the character described including, in combination: a chute arranged to contain buttons to be fed by gravity; a movable member located adjacent the lower end of said chute and having a recess therein; a staple driver slidably mounted on said member and having one end thereof slotted to receive the eye of a button; a former movable back and forth across the end of said chute and coöperable with said member to bend a piece of wire into a staple, the movements of said former timing the feeding of the buttons; and a clenching die 95 opposite which a formed staple is adapted to be brought when said member is moved, 100 substantially as specified.

9. A machine of the character described including, in combination: an oscillatable disk having a recess therein in which is slidably mounted a driver, one end of said driver being slotted to receive the eye of a button fed to the disk when the latter is in one position; a former movable into said recess and coöperable with said disk to form a piece of wire into a staple when said disk 110 is in said position; a movable clenching die; means for oscillating said disk to bring a formed staple carried thereby opposite said clenching die; and a device for reciprocating said former when the disk is in said last 115 named position, substantially as specified.

10. A machine of the character described including, in combination: an oscillatable member having a staple driver reciprocatingly mounted in a recess therein, said driver having one end thereof slotted to receive the eye of a button; a yieldingly mounted bar located adjacent said driver and carried by said member, said bar having one end thereof recessed to receive the 125 130

head of a button; a former coöperable with said member to form a piece of wire passing through the eye of a button into a staple and place the same within said recess, 5 said former coöperating with said bar to yieldingly clamp a button during the staple forming operation; a clenching die, mechanism for oscillating said member to bring the formed staple carried thereby to a position opposite the said clenching die; and a device for moving said plunger when said member is in the last named position, to thereby clench the staple to an article held between the clenching die and said member, 10 15 substantially as specified.

11. A machine of the character described including, in combination: an oscillatable disk having a staple driver reciprocatingly mounted in a recess therein; a chute arranged to contain buttons to be fed by gravity, the lower end of said chute being located adjacent the periphery of the said disk and opposite the recess therein when the disk is in one position; wire feeding 20 25 means; a movable wire cutting knife; a former coöperable with said disk and movable within the recess therein to form a staple from a severed piece of wire, said former being located adjacent the lower end 30 of said feed chute; a movably mounted clenching die; mechanism for oscillating said disk to bring a formed staple and button carried thereby to a position opposite the clenching die; and a device for moving said driver when the disk is in the last 35 named position to thereby clench the staple to an article held between the clenching die and said disk, substantially as specified.

12. In a machine of the character described, staple forming mechanism including a relatively stationary female die having a recessed portion to receive a button having an eye thereon and a movable male die arranged to move into the female die to 40 45 form a staple linked with the eye of the button, substantially as specified.

13. In a machine of the character described, staple forming mechanism including a relatively stationary female die and a reciprocating male die, the female die being provided with alined grooves on opposite sides thereof arranged parallel to the line of movement of the reciprocating male die and cut away to one side of said grooves to 50 55 receive the head of a button, said grooves

being arranged to receive parts of the staple as it is formed and to frictionally hold it and the button therewith in place, substantially as specified.

14. In a machine of the character described, wire feeding mechanism and staple forming mechanism, the latter comprising a relatively stationary female die and a reciprocating male die, the female die being provided with wire-receiving and positioning notches 54 at the outer end thereof and having a recess to receive a button in which the button is positioned before the wire is fed so that the wire, when fed, passes through the eye of the button, substantially as specified. 60 65 70

15. A button attaching machine including, in combination: automatically operated wire feeding and cutting means; a member having a recess therein adapted to be positioned adjacent the wire cutting means, said recess being large enough to receive a button to be attached; a staple former coöperable with said member and movable into a part of said recess to form a staple from a cut piece of wire passing through the eye of a button; and means coöperable with said former to hold a button in said recess during the staple forming operation, substantially as specified. 75 80 85

16. In a button attaching machine, in combination: a relatively stationary female die; means for positioning a button in said die before a staple is formed; mechanism for feeding wire through the eye of the button 90 while the latter is positioned in said die; and a male die movable into and coöperable with said female die to form the staple from the wire previously passed through the eye of the button, substantially as specified. 95

17. A machine of the character described comprising, in combination: an oscillatable member adapted to carry a button and to intermittently move from one operative position to another, a staple former coöperable with said member when in one position, and a clenching die coöperable with said member when in a second position, substantially as specified. 100 105

Signed this 22d day of September, 1913, 105 in the presence of two witnesses.

ALLEN JOHNSTON.
